SLIDE RULE FOR WALL PATTERNS AND AREAS

Frederick W. Lang, Chicago, Ill., assignor to Wood Conversion Company, Cloquet, Minn., a corporation of Delaware

Application May 26, 1941, Serial No. 395,132

2 Claims. (Cl. 235—69)

The present invention relates to a mechanical device in the nature of a slide rule, and more particularly to one relating to the application of a specific pattern, or to the selection of one of several patterns, of one or more panel units for walls, floors or ceilings.

Wall board, floor tile and ceiling panels or tile, are provided in various units, such as squares and other rectangles, which have dimensions permitting them to be fitted together in repeating pattern units to cover the area of a wall, floor or ceiling. Hereinafter, any such area is termed a "wall." Where the area to be covered is rectangular, for example, the pattern must be centered to leave spaces for borders, the width of which may be more or less than the length of a pattern unit. The border usually is a necessity in providing complete pattern units. In figuring material for such a wall, it is of importance to determine the width of border required, so that stock for it may be included with the stock for the predetermined number of pattern units. Frequently, it is found that less waste will result when selecting one pattern for a given area, than in selecting another. Thus, to figure on a job to provide the lowest cost, it becomes necessary to determine which of several available patterns will create the less waste.

It is an object of the present invention to provide a slide rule which may be manipulated to determine readily and quickly the border required for a dimension of a wall, for a given design.

It is another object of the invention to provide a rule having indications for a plurality of patterns, so that the border necessary for each pattern may be determined to permit selection of a pattern at least in part upon the basis of waste to provide a border, or upon the basis of more nearly equalizing different borders.

Still another object of the invention is to provide a rule which may be used quickly to determine the accumulated footage of wallboard material required for the pattern-units for one or all dimensions of a wall area, whereby an estimate on cost may be quickly and easily made.

Still another object of the invention is to provide a rule which may be used quickly to determine the number of tile or pattern-units along a dimension of an area, whereby the total number of such units for a whole area may be easily computed for estimating cost and for ordering the same.

Various other and ancillary objects and advantages of the invention will become apparent

from the following description and explanation of the invention, given with reference to the accompanying drawings in which:

Fig. 1 is a general view of the slide rule, partly extended, but not in an operating setting.

Fig. 2 is a view of a longitudinal cross-section of the rule positioned as in Fig. 1, on the line 2—2 of Fig. 1.

Fig. 3 is a view of a transverse cross-section of the rule of Fig. 1 on line 3—3 of Fig. 1.

Fig. 4 is an enlarged fragmentary view of a slide member of the rule of Fig. 1 showing the end and the beginning of the scale for linear dimension in feet, and with a framed opening 15 therein.

Fig. 5 is an enlarged view of one face of the slide member having the patterns which slides within the slide member of Fig. 4 to exhibit the patterns at the said framed opening.

Fig. 6 is a view of the face opposite that in Fig. 5, the bottom edge in Fig. 5 being the top edge in Fig. 6.

In the following description and explanation, and in the claims, the word "wall" is used to designate a side wall, ceiling, floor or other area, without any intention to limit the term to side walls, or the material to the so-called artificial wallboards. The invention is applicable to designs in natural wood, fiber board, veneer-panels, and any other material which may be provided in panels, blocks, tiles, or sections, each alone, or in combinations with others, or with itself, to provide pattern units which may repeat in a large wall area.

The invention, however, is specifically illustrated by reference to designs which have been in commercial use, and which are provided in a single, as well as in several varieties of a decorative fiber wallboard for side wall and for ceiling use.

The slide rule has a main body part 10 which is graduated arithmetically in units to a fixed scale to indicate length, such as feet, thus to indicate a length or width of a rectangular area 45 under consideration. For convenience this length scale, indicated at 11, is repeated at several places as indicated, both on front and on back of the body part 10. The body part 10 is shown as a flat member with a frame like form, 50 providing a through opening indicated at 12 and 13 at front and rear faces. The body part 10 is preferably made of two plies 14 and 15 secured together with spacing means 16 at the edges, so as to leave a space between the plies for a flat member 17 to slide between them for viewing its

faces 18 and 19 through the openings 12 and 13 respectively.

For several conveniences, means is provided to act as a line marker for the scales 11, whereby any selected dimension may be physically indicated. This marker functions like the usual runner or cursor with hair-line, found on mathematical slide rules, and such a structure may be provided for the body part 10. However, since in the use of the rule of the present invention, it is not necessary to read on both or either side of the marking line indicating a dimension selected on the scale 11, it is preferred to provide as a line-marker the edge of a case or envelope in which the body part 10 may be housed when not in use. Consequently, as an optional element of the invention an open-ended casing 20 is provided into which the main part is linearly slidable. The edges 21 and 22 of an end opening 23 of the casing are such that they provide line-markers across the scales 11 and the faces of the slide 17. When all the scales 11 on the main part are aligned the two edges 21 and 22 of the casing are superimposed. The casing 20 is preferably made of two plies 24 and 25, with spacing means 27 between or to which the slide member 17 is slidable.

Thus, by pulling the body part 10 out of its casing 20, the visible portion of scales 11 will indicate a definite length at the edge of the casing end. With this length set, the inner slide 17 is moved to test one or more patterns against the said indicated length. To provide for this the two faces 18 and 19 of slide 17 bear sequences of various pattern units drawn to the same scale as is used in calibrating scales 11. For example, pattern unit A is a square comprised of two rectangular units indicated as 25, and 26, each 16 x 32 inches. Alternate units of the pattern are turned 90°. This unit A repeats so that it may be fitted into the indicated dimension on scale 11 by moving the slide 17 in body part 10, until some multiple of the sequence is centered within the marked dimension. The approximate appearance of a border width, with reference to the pattern unit, may thus be seen. By placing the end 28 of A-pattern in coincidence with the zero-end of the scale 11, the actual portion of the length required for border is indicated graphically. It may be indicated also by suitable legend as shown in the A-scale 29, which refers to the A-pattern. The A-scale comprises two series of legends. One series gives the number of pattern units. The other series has legends placed at the division lines between pattern-units or along the units, showing the accumulated length of the pattern of complete units. Where the accumulated length just fits the marked dimension on the scale 11, the legend will be the same as said dimension. Where the accumulated length to the end of a unit is less than the marked dimension, the difference represents the total portion of the dimension to be bordered. Half the difference is the actual width of the border. Of course a wider border may be used by using less than the greatest possible number of complete units. The accumulated length legends for the A-pattern apply also to the B-pattern.

Another way to use the rule does not require subtraction of the accumulated length of the chosen multiple of pattern units from the room dimension, in order to derive the portion of the dimension to be fitted with border. After cen-

tering the selected multiple with respect to the room, the end edge (not the zero end) of the last unit may be moved to terminate at the set dimension of the room, whereby all the overage for border may be read on the scale 11 at the line 28 which is the zero-line for the pattern-scale. This figure plus the accumulated length of pattern will equal the room dimension. Figures directly readable are thus available for calculating board-feet or area of pattern, or board feet or area of border. Therefore, it is preferred to have the accumulated length of pattern for an advantage, however the slide member is used in practice.

15 The slide 17 has several pattern units A, B, C, D, and more may be used, with respect to each of which there is a corresponding A-scale, B-scale, C-scale and D-scale.

Thus, the several patterns may be tried against one or both dimensions of a rectangular wall, easily and quickly to find a pattern which gives near-equal borders in both directions, or one which gives the minimum of waste in cutting material to provide border, or one which gives the best appearance when bordered. The accumulated footage for both dimensions of a rectangular wall readily permits calculation of the "footage" of any pattern for the patterned area, and the border widths readily permit calculation of stock required for bordering.

16 The case 20 has been referred to as optional. It is to be understood that when dispensed with, any marker, or only a visual record, may be used to mark the dimension on scale 11 with reference to which the slide 17 is being set.

It is of course to be understood that the rule may be modified to show but one pattern, or extended to show many more patterns than are illustrated. It may be modified to function only at one face, rather than at both faces as illustrated. These and other modifications will be readily appreciated by those skilled in the art as falling within the scope of the invention as expressed in the appended claims.

45 I claim:

1. A slide rule comprising a main body, and two other parts, one of said other parts providing a line-marking-cursor, and the other part being an elongated slide member relatively slidable with respect to the main body, the main body being marked arithmetically with linear units of length for positioning the line marker to indicate one of the dimensions of a wall, the slide member being marked with one or more sequences of pattern units of wall-forming panel on the same scale-basis as the main body is marked, said slide permitting both the selection of a length of multiple units of the pattern and centering of the selected length with respect to a dimension marked on the linear scale whereby to enable visualization of the effect and proportions of the said dimension as distributed between said units and border depths, said slide also permitting movement for coincidence of one end of the selected multiple length of pattern units with one end of the said set dimension, whereby the portion of the set dimension required for border may be read.

2. A slide rule comprising a main body, and two other parts, one of said other parts providing a line-marking-cursor, and the other part being an elongated slide member relatively slidable with respect to the main body, the main body being marked arithmetically with linear

units of length for positioning the line marker to indicate one of the dimensions of a wall, the slide member being marked with one or more sequences of pattern units of wall-forming panel on the same scale-basis as the main body is marked, the accumulated lengths of the unit-patterns being marked by indicia on the slide member at the ends of pattern units, said slide member permitting both the selection of a length of multiple units of the pattern and centering of the selected length with respect to a dimension marked on the linear scale whereby to enable

5 visualization of the effect and proportions of the said dimension as distributed between said units and border depths, said slide also permitting movement for coincidence of one end of the selected multiple length of pattern units with one end of the said set dimension, whereby the portion of the set dimension required for border may be read from the scales, and the portion of the dimension required for the pattern units 10 may be read directly from said indicia of accumulated lengths.

FREDERICK W. LANG.
